ATTORNEY.

UNITED STATES PATENT OFFICE.

JOHN EDWIN JOHNSON, OF SOUTH MANCHESTER, CONNECTICUT, ASSIGNOR TO CHENEY BROTHERS, OF SOUTH MANCHESTER, CONNECTICUT, A CORPORATION OF CONNECTICUT.

FELL GAUGE FOR LOOMS.

Application filed June 24, 1924. Serial No. 722,144.

My said invention relates to a fell gauge for looms and it is an object of the same to provide a device of this character in which the degree of tension shall be indicated by a flexible scale. 5 Devices of this character are used in looms to indicate the tension of the cloth where, for example, the same has been loosened for repairing a fault in weaving or for tying broken warp ends or the like. When the cloth has 10 now been pulled down by the sand roll an element of the fell gauge is engaged with the fell of the cloth to operate the fell gauge and indicate very accurately when the cloth has been pulled tight enough for the resumption of 15 weaving.

A further object of the invention is to provide means in connection with a device of the character described whereby a fault in the position of the fell of the cloth shall be indicated 20 on the fell gauge on an enlarged scale.

Referring to the accompanying drawings, which are made a part hereof and on which similar reference characters indicate similar parts;

25 Figure 1 is a plan of my device in operative relation to the cloth.

Figure 2, a plan of the device for operating the indicating means, a part of the casing being broken away to show the interior construction;

30 Figure 3, a section on line 3—3 of Figure 1, Figure 4, a detail plan of a part shown in Figures 2 and 3,

Figure 5, a plan of the indicating means and certain parts associated therewith; and

35 Figure 6, a bottom plan of the removable cover of the casing for the gearing.

In the drawings reference character 10 indicates a support for the device which is connected in any convenient manner to the frame of the loom at one side of the forming fabric, it being shown as held in place by screws. The support has a bearing in which a bracket 11 is secured, said bracket being adjustably held by 40 set-screws 12 to permit the operative elements of the fell gauge to be properly positioned relative to the width of the cloth. The top of the bracket is preferably flattened to enable the set-screws to fix the bracket in correct position.

45 At the free end of the bracket a base or bottom member 13 of a casing is rigidly secured to the bracket. Said base member supports a post 14 preferably in the form of a screw hav-

ing threaded engagement with the base and 55 this post holds a cap 15 in place on the bottom. Between the cap and the base a chamber is provided in which a coiled spring 16 is located, said spring being secured at one end to the cap as indicated at 17 and at the other end to a 60 collar 18 held between a plate 19 and a shoulder on a pinion 25 as indicated at 20 in Figure 3, said collar having a hollow neck extending up into the central opening in plate 19.

The plate 19 lies close to the cap which is 65 provided with an arcuate slot 21 closed by a transparent window of glass or celluloid and a sheet 22 is supported between the plate and the top of the cap said sheet carrying reference numerals as indicated in Figure 5 and also 70 having a scale mark in the form of a hair line indicated at 23, said sheet being securely fastened to plate 19. The transparent window has a hair line indicated at 24, Figure 6.

The sleeve 25 has gear teeth below the collar 75 18 and said sleeve is held to the base by means of a shoulder on the screw 14. It will be understood that the construction of these parts may be varied to suit manufacturing conditions, e. g., collar 18 might be formed integral 80 with plate 19 or sleeve 25, etc., and the scale may be formed on the upper surface of the plate 19 if desired. A rack bar 26 extends through the casing alongside the pinion 25 said bar having teeth to mesh with those of the 85 pinion. At its rear end the rack bar has a yoke 27 adjustably secured thereto by means of nuts 28. A flat bar 29 or other suitable carrier is pivotally secured to the yoke by a pin 30 and said bar extends forward beyond the end of 90 the bar 26 and over a pair of cloth rolls 40, 41, to a position adjacent the fell of the cloth as indicated in Figure 1. At its forward end the flat bar carries a comb 31 which may be in one piece but is here shown as having separate claws 32 bent at their extreme ends in a manner to enable them to project down between the warps adjacent the fell of the cloth.

95 The cap 15 has oppositely positioned notches at 33 and 34 to receive the bar 26 and smaller notches 35 to receive the end 36 of a detent 37 having a thumb-piece 38. As will be seen from Figures 1 and 2 the thumb-piece is above the base, the body of the detent is below the base and the end 36 projects 100 through the same for engagement with the notches 35 of the cap. By this arrangement the bars 26 and 29 may be normally turned

to a position at right angles to that of Figure 1 where the comb 31 lies adjacent to bar 11 and distant from the fell of the cloth until the device is needed to perform the function hereinafter described. When the cloth has been wound back from the cloth beam and the defects in the weaving, etc., have been corrected the thumb-piece 38 may be depressed to release detent 36 and the cap 15 with the bars 26 and 29 and other parts may be turned to the position indicated in Figure 1 with the ends of the comb teeth projecting between the warp threads to a point below the fell of the cloth. The warp being now rewound the fell will pull the bar 29 rearward carrying with it the bar 26 and rotating the pinion 25 by its engagement with the rack bar whereupon the scale marks will pass successively beneath the window 21 until the hair line 23 registers with the hair line 24.

It will be noted that the device by means of the hair lines indicates the position of the fell very accurately and that by reason of the relation of gearing in the casing the travel of the indicating sheet 22 is much greater than the movement of the fell thus making for accuracy in the indication of position of the fell relative to the loom.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent is:

1. A fell gauge for looms comprising a support, a casing thereon, a rotary element in the casing having a hair line, a spring coiled about the axis of said rotary element for holding said element in one position, a window in the casing having a hair line adapted to register with that first mentioned, a comb adapted to engage the fell of the cloth and gearing between said comb and said rotary element for turning the same against the action of the spring, substantially as set forth.

2. A fell gauge for looms comprising a support adapted to be anchored to the frame of the loom, a comb for engaging the fell of the cloth during adjusting operations and moving in a line in the cloth plane and normal to the fell of the cloth, indicating means on a part of the support extending over the cloth, and connections between said comb and said indicating means whereby a movement of the comb causes a movement of the indicating means, substantially as set forth.

3. A fell gauge for looms comprising a bracket extending cross-wise of the loom above the cloth, a bar on the bracket movable lengthwise of the loom, a comb on the bar adapted to engage the fell of the cloth, means in the casing operable by said bar for indicating the relative position of the fell, a support for said casing at one side of the loom, and connections

engaging the fell of the cloth, indicating means on the bracket, and connections between said bar and said means whereby a right-line movement of the comb causes a movement of the indicating means, substantially as set forth. 70

4. A fell gauge for looms comprising a bracket extending crosswise of the loom, a comb adapted to engage the fell of the cloth for movement therewith, and a carrier for the comb movable about a vertical axis to place the comb into the path of the fell or to bring it into idle position alongside said support, substantially as set forth. 75

5. A fell gauge for looms comprising a bracket extending crosswise of the loom, a comb adapted to engage the fell of the cloth for movement therewith, a carrier for the comb movable about a vertical axis to place the comb in the path of the fell or to bring it into idle position alongside said bracket, and means for securing it in either of said positions, substantially as set forth. 80 85

6. A fell gauge for looms comprising a support, a casing on the support including a bottom fixed to the support and a top pivotally connected to the bottom, a comb adapted to engage the fell of the cloth, a bar carrying said comb, indicating means operated by said comb, and means for positioning the top of the casing either so as to place the comb in front of the fell of the cloth or so as to place the comb in idle position alongside the said support, substantially as set forth. 90 95

7. A fell gauge for looms comprising a bracket extending cross-wise of the loom, a bar on the bracket movable lengthwise of the loom, a carrier pivoted on the bar for movement about a horizontal axis, a comb movable with the carrier into and out of engagement with the fell of the cloth, indicating means on the bracket, and connections between said bar and said means whereby a movement of the comb causes a movement of the indicating means, substantially as set forth. 100 105 110

8. A fell gauge for looms comprising a support, a bar movable in the direction of travel of the cloth, a comb on the bar for engaging the fell of the cloth and movable in the cloth plane in a line normal to the fell, indicating means on the support including an oscillatory element, connections between the comb and the oscillatory element whereby a movement of the comb causes a magnified movement of the indicating means, and resilient means for returning said element to its zero position, substantially as set forth. 115 120

9. A fell gauge for looms comprising a casing, a bar mounted on the casing for movement lengthwise with the cloth in the loom, means movable with the bar adapted to engage the fell of the cloth, means in the casing operable by said bar for indicating the relative position of the fell, a support for said casing at one side of the loom, and connections 125 130

between the casing and the support adjustable crosswise of the loom, substantially as set forth.

10. A fell gauge for looms comprising a support, a carrier mounted thereon for movement about a horizontal axis, a comb at the free end of the carrier said carrier being also movable about a vertical axis to bring the comb into idle position, substantially as set forth.

11. A fell gauge having means to anchor it to a fixed part of the loom, a comb engageable with the fell of the cloth to be moved thereby in a horizontal right line and indicating means operable by said comb, substantially as set forth.

12. A fell gauge having means to anchor it to a fixed part of the loom, a comb engageable with the fell of the cloth and following the movements of such fell bodily in a line normal to the fell of the cloth and coinciding with the cloth plane, and indicating means operable by said comb, substantially as set forth.

13. A cloth setting device for looms comprising a spring held feeler comb movable longitudinally of the warp and adapted to engage therewith, means supporting said comb

for vertical swinging movement into and out of engagement with the warp and against movement transversely of the warp during engagement therewith, an indicator member, and another indicator member movable with the comb relative to the first indicator member.

14. A cloth setting device for looms comprising a comb, means supporting said comb for bodily vertical swinging movement and for angular movement relative to the pivotal axis of said means longitudinally of the warp, said comb adapted to be swung downwardly and engaged through the warp and against the forward edge of the woven cloth, said supporting means adapted to prevent movement of the comb transversely of the warp during engagement therewith, an indicator member, and another indicator member actuated by the comb in the longitudinal movement thereof with respect to the first indicator member.

In witness whereof, I have hereunto set my hand at South Manchester, Connecticut, this 19th day of June, A. D. nineteen hundred and twenty-four.

JOHN EDWIN JOHNSON.
